UNITED STATES PATENT OFFICE.

PRINCE A. GARDNER, OF ST. LOUIS, MISSOURI.

EMBOSSING-MACHINE.

1,143,379.

Specification of Letters Patent. Patented June 15, 1915.

Application filed October 28, 1914. Serial No. 869,076.

To all whom it may concern:

Be it known that I, PRINCE A. GARDNER, a citizen of the United States, residing at the city of St. Louis, State of Missouri, have invented certain new and useful Improvements in Embossing-Machines, of which the following is a specification.

This invention relates to presses for embossing, or otherwise marking articles and relates, more particularly, to hand operated presses for embossing, impressing, stamping, or otherwise marking characters, words, designs, and the like upon book-covers, card cases, purses, suit cases, bags, valises, harness, and many other articles of leather, cloth, and the like.

An object of the present invention is to provide an apparatus of the character described of simple, cheap, and strong construction, which is efficient in operation, of great power simply and evenly applicable, which will quickly and readily produce clear, even work in embossing, impressing, stamping, or otherwise marking articles, and which is adjustably adapted to do such work upon articles of many different shapes and sizes.

A further object is to provide, in an apparatus of the character described, means for conveniently embossing, impressing, stamping, or otherwise marking upon a surface of material, such, for instance, as leather of uneven thickness.

Another object of the present invention is to provide a press of the character described mounted upon a slidable leaf of a table hereinafter described in the manner and for the purpose set forth in this specification.

In the accompanying drawings forming part of this specification wherein like numbers of reference denote like parts wherever they occur, Figure 1 is a side view, partly in elevation and partly in section, of a press and associated parts embodying this invention (a part of the operating lever being broken away) with the slidable leaf and the table shown in Fig. 5 removed therefrom; Fig. 2 is a plan view looking down upon the adjustable straight-edge device and associated parts, the upwardly extending standard being shown in section on the line 2--2, Fig. 1, and the parts above said line shown in Fig. 1 having been removed from said plan view; Fig. 3 is a front view in elevation of an apparatus embodying the present

invention, a portion of the operating lever having been broken away, showing a separable rocker member supported on the base of the apparatus, part of said base adjacent to a pin hole being broken away to show the means of supporting a depending pin of said member in the pin hole of said base; Fig. 4 is a fragmentary side view, partly in plan and partly in section, showing particularly the lower portion of the plunger stem and parts associated therewith; Fig. 5 is a plan view looking down upon the slidable table and the slidable leaf thereof from which the press shown in Fig. 1 has been removed; Fig. 6 is a sectional view on the line 6--6, Fig. 5; Fig. 7 is a sectional view of the table shown in Fig. 5 on the line 7--7, Fig. 5, with the press (Fig. 1) mounted on said table, showing, also, in dotted lines the position of said press and the slidable leaf when the slidable leaf supporting said press is moved forward toward the operator.

A base-plate 1 has a rearward extension 2, said extension bearing a pair of lugs 3 (one lug on each side of said extension as best seen in Fig. 2), an upwardly extending forwardly curved arm or standard 4, said arm bearing casing 5 and pivotal bearing 6, said bearing being adapted pivotally to support the fulcrum end of operating lever 7. Casing 5 is preferably of hollow cylindrical construction open at both ends and made in two vertically divided halves (as best seen in Fig. 1) the two halves being removably attached to each other by any suitable means, such, for instance, as by means of bolts 8 clamping together opposite pairs of laterally extending perforated flanges borne by the halves of said casing. A vertically perforated lug 10 is preferably provided borne by the rearward upper portion of casing 5 the perforation of said lug being screw-threaded and adapted to receive an adjusting screw 11, said screw being adapted adjustably to limit the downward movement of lever 7. Base-plate 1, extension 2, lugs 3, arm 4, the rearward half of casing 5 with its flanges 8 and lug 10, and pivotal bearing 6 are preferably a metallic casting made in one piece.

The interior of casing 5 is preferably provided with an inwardly extending annular shoulder 12 adjacent to each end of said casing, that is the opening at each end of

said easing is reduced by the width of said shoulder to a less diameter than that of the remaining interior hollow portion of said casing between said shoulders, each of said reduced portions at each opening being adapted to form a bearing for plunger stem 13 (preferably of hollow cylindrical construction), said stem being adapted to extend vertically through said hollow casing with an end protruding above and below same and being slidable downward and upward in its bearings in said casing. The lower end of said stem may be provided with an enlarged portion bearing a shoulder 14, said shoulder abutting upon an adjacent edge of the end of casing 5 when said stem is in normal position as shown in the drawings, said stem being held in that position under tension of spiral spring 15, said spring being supported upon lower shoulder 12 in casing 5 and the upper portion of said spring preferably resting against the protruding ends of a pin 16 or the like inserted transversely through stem 13 adjacent the upper portion of said stem. The upper end of plunger stem 13 may be provided with an antifriction roller 17 revolvably supported in the hollow of said stem by means of a pin 18 or the like inserted transversely through said stem, and, to provide clearance for an adjacent portion of lever 7 in operating same, a downwardly inclined slope 19 may be provided on the rearward portion of the upper end of stem 13, so that when power is applied to the power end of lever 7, a surface of said lever adjacent its load will be in contact with said anti-friction roller and cause said roller to rotate, thus facilitating the depression of stem 13 against the tension of spring 15. Plunger stem 13 is held in position against rotary motion in its bearings by any suitable means, such, for instance, as by means of pin 15^a protruding into the interior of casing 5 through an appropriate opening in said casing, the inwardly protruding end of said pin being adapted slidably to engage a vertical groove in said plunger-stem. The enlarged lower portion of stem 13 bearing shoulder 14 is provided with a forward extension 20 protruding horizontally forward beyond the front of casing 5, said extension bearing two oppositely disposed laterally extending arms 21 and a forwardly extending nose 22, said nose having preferably a flat under surface and curved sides bearing a flat ridge as best seen in Fig. 3. Nose 22 is adapted to enter the arched opening of pallet or holder 23, said holder being held firmly in place on said nose against adjacent portions of arms 21 by means of wedge 24 inserted into the space formed between the flat ridge of nose 22 and the curve of the arch of said arched opening of said pallet or holder 23. Pallet or holder 23 is of the ordinary construction

usually employed in marking articles by hand, and is adapted to hold the type, characters, design, die or the like desired to be embossed, stamped, impressed or otherwise marked upon the book-cover or other articles placed thereunder, said pallet or holder being preferably provided with jaws 24 adapted to hold said type, characters, design, die or the like in central position, said jaws being adjustable upon right and left screw-threaded bar 25 by means of manipulating either of finger pieces 26 in the usual manner.

Straight-edge 27 is adapted to form an upright wall facing the operator and extending laterally across the surface of base-plate 1, or separable platform 28, the upright wall of said edge being preferably of substantially equal height to the height of lugs 3 above the surface of said base-plate, a convenient height having been found in practice to be about seven-eighths ($\frac{7}{8}$) of an inch, and said edge being slidably adjustable toward and away from the operator by any suitable means, such, for instance, as by means of a pair of rearwardly extending slotted guiding arms 29 of any suitable length borne by said edge at portions thereof adjacent to one of its long side edges. Thumb-screws 30 inserted through the slot of each of said arms into appropriate holes in lugs 3 may be provided to furnish convenient means for sliding said edge forward and backward upon its guiding arms and securing same in any desired adjusted position. The height of lugs 3 are adapted to permit straight-edge 27 to be used with the long side-edge bearing arms 29 as its base when separable platform 28 is in place on base-plate 1 (Figs. 1 and 2), and to permit said straight-edge to be reversed, as shown in Fig. 7, with the non-arm-bearing long side-edge as the base.

A car 31 having a grooved portion adapted to straddle straight-edge 27, as best seen in Fig. 1, may be provided, said car having preferably two parallel walls adapted to extend forward from said edge at a right-angle thereto as best seen in Fig. 2, said car being slidable along said edge and being adapted to be set securely in any adjusted position along said edge by any suitable means, such, for instance, as by means of thumbscrews 32 whose inner end is adapted to press against an adjacent portion of said edge, said screw preferably passing through a perforated lug 33 (the perforation being screw-threaded) borne by the rear wall of the straddling portion of said car 31. The two parallel walls of car 31 permit same to be used as a guide for squaring articles to be marked convenient to the right hand or left hand of the operator.

It has been found difficult, by the means ordinarily employed, to obtain a satisfactory

impression, stamp, emboss, or mark upon an article, such, for instance, as a card-case, where one portion underneath the surface desired to be worked upon is thicker than another. To avoid this difficulty in a press embodying the present invention, a separable platform 34 may be provided, said platform having a flat upper surface and a rocker-shaped lower surface, as best seen in Fig. 3, said platform being rockably held in place upon base-plate 1 by means of pins 35 (preferably in a position diagonally opposite each other) depending from the under surface of said platform and entering into suitable holes 36 in base-plate 1, said holes being sufficiently large to permit lateral play of said pins therein as said platform is rocked in operating the press as hereinafter described. In order to permit of the satisfactory use of straight-edge 27 and parts associated therewith and to provide a surface level rearwardly with the surface of rockered platform 34, a second separable platform 28 to the rear of rockable platform 34 may be provided, said separable platform 28 being substantially of similar thickness as that of rockered platform 34 (in practice a thickness of about seven-eighths of an inch has been found satisfactory for ordinary purposes), and said separable platform 28 may be provided with pins 37 (preferably in a position diagonally opposite each other) depending from the under surface of said platform and adapted to enter suitable holes therefor in base-plate 1 to hold said platform 28 in place upon said base-plate.

In operating the press with rockable member 34 and separable platform 28 in place on base-plate 1 as just described, the article to be marked having been placed on rockered platform 34, straight-edge 27, and car 31 having been moved to and set in proper position to permit the operator to hold said article true and square with reference to the die or the like previously secured in holder or pallet 23 in adjusted position, and said pallet having been wedged in place upon nose 22, power is applied to the power end of lever 7 and said lever is pressed downwardly upon anti-friction roller 17 borne at the upper end of plunger-stem 13, whereupon said stem slides downwardly in its bearings against the tension of spring 15, thus moving pallet or holder 23 with its die downward toward the article to be marked, and as the downward pressure of lever 7 is continued, the downward movement of said stem and holder or pallet continues until the die in said holder or pallet presses upon the upper surface of the article on rockered platform 34 and as the pressure continues, rockered platform rocks as the die presses upon the unequal thickness of said article thus presenting all

portions of the surface of said article to be marked equally to appropriate parts of said die or the like producing a clear even mark of said die or the like upon said article. When the mark has been made upon the article as described, the power is released from the power end of lever 7, whereupon plunger-stem 13 under tension of spring 15 recedes to normal position lifting said lever, and, also, withdrawing holder or pallet 23 with its die away from the marked article.

By manipulating adjusting screw 11, by screwing same out or in, the downward throw of lever 7 may be limited so that when a portion of said lever adjacent said screw strikes the top of said screw in the downward stroke of said lever further downward movement will be arrested, thus limiting, also, the downward stroke of plunger-stem and the downward movement of pallet or holder 23 with its die or the like. In this way, when the operator is marking a number of similar articles with the same die or the like, he may, having ascertained the degree of downward throw of lever 7 suitable for producing a mark satisfactory upon one of said articles, set adjusting screw 11 in position to limit the downward throw of said lever to the degree of throw desired and thus insure the marking of all the similar articles equally and alike.

Table 38 (shown in plan view in Fig. 5, and in sectional views in Figs. 6 and 7) made of any suitable material, such, for instance, as wood, may be constructed of two parallel side plates 39 and 40 of similar width, thickness, and length spaced suitable distances apart to admit therebetween slidable leaf 41, which slidable leaf is herein-after more particularly described. Extending over the tops of the rear end portions of said plates 39 and 40 and over the space between said plates, a transverse top end-plate 42 is placed and secured in place by any suitable means, such, for instance, as by being nailed or bolted to said plates 39 and 40, and underneath the rear end portions of said plates 39 and 40, a bottom end-plate 43, which may be similar in length, width, and thickness to said top end-plate 42, may be placed transversely across said plates 39, 40, and the space therebetween, said bottom end-plate being secured in place by any suitable means, such, for instance, as by means of nailing or bolting same to said plates 39 and 40. By means of this construction, a covered channel, open at the rear and forward ends, will be formed, the bottom of said channel being the upper surface of a portion of bottom end-plate 43 between side plates 39 and 40, the top of said channel being the under surface of a portion of top end-plate 42 between side plates 39 and 40, and the sides of said channel being portions of the side edges of said

125
130

plates 39 and 40, the forward end opening of said channel communicating with the space between said plates 39 and 40. At the forward ends of said side plates 39 and 40, a front end bottom-plate 44 may be provided of similar thickness as that of rear end bottom-plate 43 and which may, also, be similar to said rear end bottom-plate 43 in its other dimensions, said front end bottom-plate being placed transversely across the bottom of the front end portions of side plates 39 and 40, and across the space therebetween, slightly overlapping the under surface of said portion of said side plates and 15 extending forwardly beyond the front ends of said side plates, said front end bottom-plate being secured in place by any suitable means, such, for instance, as by being nailed or bolted to said side plates. Three front 20 end top-members 45, 46, and 47 may be provided, said members being adapted each to rest upon a portion of the upper surface of front end bottom-plate 44 adjacent, respectively, to said three members, members 25 45 and 46 being plates of similar dimensions placed upon and bolted or otherwise secured to front end bottom-plate 44 with the rear edge of member 45 abutting against the front edge of side plate 39 and with the 30 rear edge of member 47 abutting against the front edge of side plate 40, said members 45 and 47 being preferably each of a similar thickness to that of plates 39 and 40, and being spaced apart a similar distance 35 to that at which side plates 39 and 40 are spaced apart. Member 46 is preferably hinged to member 47 as shown in Figs. 5 and 6, and is adapted removably to cover the space between members 45 and 47, so 40 that when said hinged member is in position resting upon the adjacent portion of the upper surface of front end bottom-plate 44 (as best seen in Figs. 5 and 6), the upper surface presented by members 45, 46, and 45 47 will be substantially an even one, and when hinged member 46 is swung upwardly on its hinged attachment in the arc dotted in Fig. 6, the space between members 45 and 47 will register with the space between 50 side plates 39 and 40, it being understood that the rear edge of hinged member 46 is in line with the rear edges of members 45 and 47.

Slidable leaf 41 is adapted to fit in the 55 space between side plates 39 and 40 and preferably extends from the rear edge of hinged member 46 (when said member is in closed position best seen in Fig. 5) rearwardly through the closed channel, above 60 described, and beyond the rear ends of rear end top and bottom-plates 42 and 43 for a sufficient distance so that rear end 48 and a portion of leaf 41 adjacent to said rear end 48 may be between said rear top and 65 bottom-plates in said channel when said

slidable leaf is moved forward between plates 39 and 40 and between members 45 and 47 in the manner and for the purpose hereinafter described. The space on slid- 70 able leaf 41 (when said leaf is in the position shown in Fig. 5 and in the full lines in Fig. 7 with hinged member 46 in closed position) between the rear edge of hinged member 46 and the forward edge of rear top-plate 42 is of a size adapted to receive 75 base-plate 1 and base-plate extension 2, said base-plate and said extension being preferably secured to said leaf in said space by any suitable means, such, for instance, as by means of screws or bolts through appropriate openings 49, in said extension 2 shown in Fig. 2. Thus the press hereinabove described will be supported on said slidable leaf in the position shown in Fig. 7. When said slid- 80 able leaf with the press thereon 85 is in the position shown in the full lines, Fig. 7, a separable slab 50, of a thickness equal to the height of the upper surface of base-plate 1 above the upper surface of hinged member 46, may be provided and 90 may be held in place by means of pins 51 depending from the under surface of said slab and adapted to enter appropriate holes 52 therefor in said hinged member 46, said pins being preferably two in diagonally opposite positions on the bottom of said slab, the purpose of said slab being to provide an even surface extension forward from the 95 forward end of base plate 1.

In case rockered platform 34 is used on 100 base-plate 1 of a press in the position shown in full lines, Fig. 7, slab 50 may be made of sufficient thickness so that its upper surface will be substantially level with the upper surface of rockered platform 34 when said 105 platform is in even balanced level position.

In operation, movable leaf 41 being, with the press thereon, in the position last above-described, and table 38 having thereon slab 50, holder or pallet 23 with type, character, 110 design, die or the like held therein being in place upon nose 22, the article desired to be marked may be placed on base-plate 1 under said holder, said article being squared into proper place and position by means of straight-edge 27 and the arms of car 31 (said edge and said car having been moved to and set in an adjusted position), power is applied to the power end of lever 7 to pull 115 said lever downward upon its load, whereby plunger-stem 13 is moved downward against the tension of spring 15 thus bearing downward, also, pallet or holder 23 and the die or the like being pressed against the surface of the article on base-plate 1, lever 7 being 120 forced downward with suitable power, said article is quickly marked as desired. The power may then be released from the power-end of lever 7, whereupon stem or plunger 125 13 will recede upwardly under tension of 130

spring 15 to normal position shown in the drawings, thus elevating lever 7 (the tension of spring 15 being preferably sufficient therefor) and lifting holder 23 upwardly 5 away from the marked article.

It is sometimes inconvenient to mark an article because of its bulk or for some other reason, when slideable leaf 41 and the press thereon is in the position shown in the full lines in Fig. 7, and, therefore, the present invention provides that said leaf with the press thereon may be slid forward through the passage formed by swinging the free end of hinged member 46 open on the dotted line 10 15 arc shown in Fig. 6, thus removing said hinged member from the upper surface of front end-plate 44 between members 45 and 47, and thus removing said hinged member out of the path of slideable leaf 41 in its forward movement. Slideable leaf 41 with the press thereon may then be slid forward from the full line position shown in Fig. 7 to the dotted line position shown in said figure, and in this new position the front edge of 20 25 base-plate 1 and slideable leaf 41 will protrude forward beyond the front edges of members 45, 46, and 47 thus making convenient the marking of an article, such, for instance, as a suit-case by permitting said 30 35 suit-case to be opened and hung over the forwardly protruding end-portion of said base-plate and facilitating the marking of any desired portion of the outer surface of said suit-case by operating the press in the manner hereinabove described.

It is, of course, understood that, if desired, rocker platform 34 and separable platform 28 may be used (in which case straight-edge 27 and parts associated therewith are 40 45 used in the position shown in Figs. 1 and 2) either when slideable leaf 41 with the press thereon is in the position shown in the full lines in Fig. 7 or when same is in the position shown in the dotted lines in said figure, and, also, that in either of said positions of 50 55 said leaf and press the upper surface of base-plate 1 may be used as the operating platform, said separable platform 28 and said rocker platform 34 being removed, and straight-edge 27 reversed to the position thereof illustrated in Fig. 7.

Among the many advantages provided by the present invention, some that may be particularly mentioned are, that: The slideable leaf with the press thereon facilitates marking upon articles of practically all shapes and sizes with said press; the rocker platform provides an effective and simple means for marking articles of uneven thickness 60 65 with an even mark; the adjustable limiting device 11 effectively limits, in a simple manner, the degree of the downward throw of lever 7, the downward stroke of plunger-stem 13, and the downward movement of holder or 70 75 80 85 90 95 100 105 110 115 120 125 130 pallet 23 toward the article on the operating

platform; and the spring control of the plunger-stem automatically recedes said holder or pallet from contact with a marked article when the power is removed from the power-end of lever 7.

70

Many changes in the details of construction and arrangement of parts may be made without departing from the nature and spirit of the present invention.

I claim:

1. In a press of the character described, a casing, a plunger slideable vertically in said casing and protruding above and below the latter through oppositely disposed openings therein, means borne by the lower portion of said plunger adapted to limit the upward movement of the latter, a spring borne by said plunger adapted normally to hold the plunger in position against upward movement, a lever adapted to exert power against the tension of said spring, a forwardly protruding nose borne by the lower portion of said plunger outside of said casing, a die-support mounted on said nose, and a wedge associated with said die-support and 80 85 90 nose and movable in a direction at right angles to said plunger.

2. In a press of the character described, a casing, a plunger slideable vertically in said casing, said plunger protruding above and below said casing through oppositely disposed openings therein, means borne by the lower portion of said plunger adapted to limit the upward movement of said plunger, a spring borne by said plunger, said spring being adapted normally to hold said plunger in position against downward movement, a lever adapted to exert power against the upwardly protruding end of said plunger to move said plunger downwardly against 100 105 the tension of said spring, and a forwardly protruding nose borne by the lower portion of said plunger outside of said casing, said nose having a flat base and arched sides converging to a flat ridge, a type carrier supported on said nose, and a wedge positioned on the flat ridge engaging the type carrier.

3. In a press of the character described, a casing, a plunger slideable vertically in said casing, said plunger protruding above and below said casing through oppositely disposed openings therein, means borne by the lower portion of said plunger adapted to limit the upward movement of said plunger, a spring borne by said plunger, said spring being adapted normally to hold said plunger in position against downward movement, a lever adapted to exert power against the upwardly protruding end of said plunger to move said plunger downwardly against 120 125 the tension of said spring, a forwardly protruding nose borne by the lower portion of said plunger outside of said casing, and a holder for dies and the like, said holder having an opening adapted to admit said

- 6 nose therethrough removably to support said holder and an axially movable wedge associated therewith adapted to hold the nose and die holder relatively immovable.
- 5 4. In a press of the character described, a casing, a plunger slidable vertically in said casing, said plunger protruding above and below said casing through oppositely-disposed openings therein, means borne by the 10 lower portion of said plunger adapted to limit the upward movement of said plunger, a spring borne by said plunger, said spring being adapted normally to hold said plunger in position against downward movement, a lever adapted to exert power against the upwardly protruding end of said plunger to move said plunger downwardly against the tension of said spring, and a forwardly protruding nose borne by the lower portion 15 of said plunger outside of said casing, said nose having a flat base and arched sides converging to a flat ridge, a holder for dies and the like, said holder having an opening adapted to admit said nose therethrough 20 to support said holder, and a wedge adapted to enter a space in said opening between the flat ridge of said nose and an adjacent portion of said holder removably to hold said holder firmly in place on said nose.
- 25 5. In a press of the character described, the combination with a base-plate adapted to support the article to be marked, of a rearward extension of said base-plate, a pair of lugs borne by said extension, a movable straight-edge borne by said base-plate extending beyond the side edges of the same and a pair of rearwardly extending arms borne by said straight-edge formed integral therewith having an elongated guide-opening 30 therein, each arm being slidably supported by a corresponding one of said pair of lugs, each lug bearing a screw-threaded member protruding through the guide-opening of an adjacent arm and being adapted 35 to engage said opening to permit said straight-edge to be moved forward and backward upon said base-plate, said screw-threaded member being, also, adapted to lock said straight-edge in a set position.
- 40 45 6. In a press of the character described, the combination with a base-plate adapted to support the article to be marked, of a rearward extension of said base-plate, a pair of lugs borne by said extension, a movable straight-edge borne by said base-plate, and a pair of rearwardly extending arms borne by said straight-edge having an elongated 45 guide-opening therein, each arm being slidably supported by a corresponding one of said pair of lugs, each lug bearing a screw-threaded member protruding through the 50 guide-opening of an adjacent arm and being adapted to engage said opening to permit said straight-edge to be moved forward and backward upon said base-plate, said
- 55 60 65 screw-threaded member, being also, adapted to lock said straight-edge in a set position, a slotted member slidably supported in its slot by said straight-edge, a pair of forwardly extending parallel arms borne by 70 said slotted member, each of said arms having a lateral wall substantially at a right-angle to said straight-edge, and a screw-threaded member borne by said slotted member, said screw-threaded member being 75 adapted to lock said slotted member in a set position on said straight-edge.
7. In a press of the character described, the combination with a base-plate therefor, of a rockered-bottom platform removably 80 borne by said base-plate and loosely connected thereto at two different points, said platform having a flat upper surface adapted to support thereon the article to be marked.
8. In a press of the character described, the combination with a base-plate therefor, of a rockered-bottom platform removably borne by said base-plate, said platform having an upper surface adapted to support thereon 90 an article to be marked, and a plurality of depending members borne by the rockered-bottom of said platform, each of said depending members being adapted to enter an adjacent opening in said base-plate to hold 95 said platform in place upon said base-plate, said openings being sufficiently large to permit lateral play of the depending member therein as said platform is rocked.
9. In a press of the character described, 100 the combination with a base-plate therefor, of a rockered-bottom platform removably borne by said base-plate, said platform having an upper surface adapted to support thereon an article to be marked, and a pair 105 of depending members borne by the rockered-bottom of said platform, said depending members being in a position relatively diagonal to each other and each being adapted to enter one of a pair of openings 110 in said base-plate to hold said platform in place on said base-plate, each of said openings being sufficiently large to permit lateral play of the depending member therein when said platform is rocked.
- 115 10. In a press of the character described, the combination with a base-plate therefor, of a rockered-bottom platform removably borne by the forward portion of said base-plate, the upper surface of said platform being adapted to support the article to be marked, and a flat-bottomed platform removably borne by said base-plate and extending thereon rearward the rockered-bottom platform, the upper surface of said flat-bottomed platform being substantially level with the upper surface of said rockered platform when said rockered-bottom platform is in evenly balanced position on its rockered-bottom.
- 120 125 130 135

11. In a press of the character described, the combination with a base-plate therefor, of a rocker-bottom platform removably borne by the forward portion of said base-plate, the upper surface of said platform being adapted to support the article to be marked, means depending from the rocker-bottom of said platform adapted to enter appropriate openings in said base-plate to hold said platform in place thereon, said openings being sufficiently large to allow lateral play of said depending means as said platform is rocked, a flat-bottom platform removably borne by said base-plate and extending rearward the rocker-bottom platform, the upper surface of said flat-bottom platform being substantially level with the upper surface of said rocker-bottom platform when said rocker-bottom platform is in evenly balanced position on its rocker bottom, and means depending from said flat-bottom platform adapted to enter appropriate openings in said base-plate to hold said flat-bottom platform in place.
12. In a press of the character described, the combination with a base-plate therefor, said base-plate having a rearward extension, of a rocker-bottom platform removably borne by the forward portion of said platform, a flat-bottom platform removably borne by said base-plate and extending thereon rearward the rocker-bottom platform, the upper surface of said flat-bottom platform being substantially level with the upper surface of said rocker-bottom platform when the latter is in evenly balanced position on its rocker-bottom, a pair of lugs borne by said rearward extension of said base-plate, a straight-edge adapted to rest on said flat-bottom platform, a pair of rearwardly extending arms borne by said straight-edge, each arm having an elongated guide-opening therein and being slidably supported by a corresponding one of said pair of lugs, and a screw-threaded member borne by each lug and protruding through the guide-opening of an adjacent arm, said member being adapted slidably to engage said opening to permit said straight-edge to be moved forward and backward upon said platform, said screw-threaded member being, also, adapted to lock said straight-edge in a set position, a slotted member slidably supported in its slot by said straight-edge, a pair of forwardly extending parallel arms borne by said slotted member, each of said arms having a lateral wall substantially at a right-angle to said straight-edge, and a screw-threaded member borne by said slotted member, said screw-threaded member being adapted to lock said slotted member in a set position on said straight-edge.
13. In a press of the character described, the combination with a base-plate therefor, said base-plate having a rearward extension, of a rocker-bottom platform removably borne by the forward portion of said platform, a flat-bottom platform removably borne by said base-plate and extending thereon rearward the rocker-bottom platform, the upper surface of said flat-bottom platform being substantially level with the upper surface of said rocker-bottom plat-

- form when the latter is in evenly balanced position on its rocker-bottom, a pair of lugs borne by said rearward extension of said base-plate, a straight-edge adapted to rest on said flat-bottom platform, a pair of rearwardly extending arms borne by said straight-edge, each arm having an elongated guide-opening therein and being slidably supported by a corresponding one of said pair of lugs, a screw-threaded member borne by each lug and protruding through the guide-opening of an adjacent arm, said member being adapted slidably to engage said opening to permit said straight-edge to be moved forward and backward upon said platform, said screw-threaded member being, also, adapted to lock said straight-edge in a set position, a slotted member slidably supported in its slot by said straight-edge, a pair of forwardly extending parallel arms borne by said slotted member, each of said arms having a lateral wall substantially at a right-angle to said straight-edge, and a screw-threaded member borne by said slotted member, said screw-threaded member being adapted to lock said slotted member in a set position on said straight-edge.
14. A press of the character described, having a base-plate, a rearward extension of said base-plate, an upwardly and forwardly turned arm borne by said extension, a pivotal bearing supported by said arm, a lever pivotally fulcrumed in said bearing, a casing borne by the forward end of said arm above said base-plate, a plunger slideable vertically in said casing, said plunger protruding above and below said casing through oppositely disposed openings therein, means borne by the lower portion of said plunger adapted to limit the upward movement of said plunger, a spring borne by said plunger, said spring being adapted normally to hold said plunger in position against downward movement, said lever being adapted to exert power against the upwardly protruding end of said plunger downwardly against the tension of said spring, a vertical groove in said plunger, an inwardly protruding member borne by said casing, said member being adapted to engage said groove in slidable relation therewith to prevent rotary movement of said plunger in its bearings in said casing, a forwardly protruding nose borne by the lower portion of said plunger outside of said casing, said nose having a flat base and arched sides converging to a flat ridge, a holder for dies and the like removably borne by said nose, said holder having an opening adapted to admit said nose therethrough, and a wedge adapted removably to enter a space in said opening between the flat ridge of

said nose and an adjacent portion of said holder to hold said holder firmly in place on said nose.

15. A press of the character described supported on the slidable leaf of a table, said table consisting of a pair of side guide-members spaced apart sufficiently to support said slidable leaf in slidable relation with said guide-members, a pair of transverse members, one borne by the upper surface of the rear portions of said guide-members and the other borne by the under surfaces of said rear portion, said transverse members with said side guide-members being adapted to 10 form a covered channel for said slidable leaf, said channel having a rearward and a forward opening, said forward opening communicating with the uncovered space between said guide-members, said slidable leaf being of sufficient length to extend from the front end of said side guide-members rearwardly through said covered channel and beyond the rearward opening of said channel, a front-end transverse member borne by a portion of the under surface of said guide-members adjacent to the forward end thereof, said front-end transverse member extending forward beyond the front-end of said guide-members, a pair of members borne by the upper surface of said front-end transverse member, said pair of members being spaced apart at a distance similar to that at which said side guide-members are spaced apart and the rear edge of each of said pair of members abutting upon the front edge of an adjacent side guide-member, a middle member removably supported on the upper surface of said front-end transverse member in the space between said pair of members, said middle member having one side-edge hinged to an adjacent side-edge of one of said pair of members, the other side-edge of said middle member being free to swing upward and away from the adjacent side-edge of the other of said pair of members to permit the space between said pair of members to be cleared for the passage therethrough of said slidable leaf as said slidable leaf is moved forward, said middle member being of a thickness substantially equal to that of said slidable table, and a slab removably borne by the upper surface of said middle-member, said slab being of sufficient thickness to form a level surface with the upper surface of the base-plate of the press. 15 20 25 30 35 40 45 50 55 60 65 70 75 80 85 90 95 100 105 110 115 120 125 130

17. A press of the character described supported on the slidable leaf of a table, said table consisting of a pair of side guide-members spaced apart sufficiently to support said slidable leaf in slidable relation with said guide-members, a pair of transverse members, one borne by the upper surface of the rear portions of said guide-members and the other borne by the under surfaces of said rear portion, said transverse members with said side guide-members being adapted to form a covered channel for said slidable leaf, said channel having a rearward and a forward opening, said forward opening communicating with the uncovered space between said guide-members, said slidable leaf being of sufficient length to extend from the front end of said side guide-members rearwardly through said covered channel and beyond the rearward opening of said channel, a front-end transverse member borne by a portion of the under surface of said guide-members adjacent to the forward end thereof, said front-end transverse member extending forward beyond the front-end of said guide-members, a pair of members borne by the upper surface of said front-end transverse member, said pair of members being spaced apart at a distance similar to that at which said side guide-members are spaced apart and the rear edge of each of said pair of members abutting upon the front edge of an adjacent side guide-member, a middle member removably supported on the upper surface of said front-end transverse member in the space between said pair of members, said middle member having one side-edge hinged to an adjacent side-edge of one of said pair of members, the other side-edge of said middle member being free to swing upward and away from the adjacent side-edge of the other of said pair of members to permit the space between said pair of members to be cleared for the passage therethrough of said slidable leaf as said slidable leaf is moved forward. 15 20 25 30 35 40 45 50 55 60 65 70 75 80 85 90 95 100 105 110 115 120 125 130

- bers being spaced apart at a distance similar to that at which said side guide-members are spaced apart and the rear edge of each of said pair of members abutting upon the front edge of an adjacent side guide-member, a middle member removably supported on the upper surface of said front-end transverse member in the space between said pair of members, said middle member having one 5 side-edge hinged to an adjacent side-edge of one of said pair of members, the other side-edge of said middle member being free to swing upward and away from the adjacent side-edge of the other of said pair of members to permit the space between said 10 pair of members to be cleared for the passage therethrough of said slidable leaf as said slidable leaf is moved forward, and a slab removably borne by the upper surface 15 of said middle member, the thickness formed by said middle member and said slab thereon being sufficiently great to bring the upper surface of said slab substantially on a level with the upper surface of the working platform of the press.
18. A press of the character described supported on the slidable leaf of a table, said table consisting of a pair of side guide-members spaced apart sufficiently to support 20 said slidable leaf in slidable relation with said guide-members, a pair of transverse members, one borne by the upper surface of the rear portions of said guide-members and the other borne by the under surfaces of 25 said rear portion, said transverse members with said side guide-members being adapted to form a covered channel for said slidable leaf, said channel having a rearward and a forward opening, said forward opening 30 communicating with the uncovered space between said guide-members, said slidable leaf being of sufficient length to extend from the front end of said side guide-members rearwardly through said covered channel and 35 beyond the rearward opening of said channel, a front-end transverse member borne by a portion of the under surface of said guide-members adjacent to the forward end thereof, said front-end transverse member extending forward beyond the front-end of said 40 guide-members, a pair of members borne by the upper surface of said front-end transverse member, said pair of members being spaced apart at a distance similar to that 45 at which said side guide-members are spaced apart and the rear edge of each of said pair of members abutting upon the front edge of an adjacent side guide-member, a middle member removably supported on the upper 50 surface of said front-end transverse member in the space between said pair of members, said middle member having one side-edge hinged to an adjacent side-edge of one 55 of said pair of members, the other side-edge of said middle member being free to swing upward and away from the adjacent side-edge of the other of said pair of members to 60 permit the space between said pair of members to be cleared for the passage therethrough of said slidable leaf as said slidable leaf is moved forward, a slab removably borne by the upper surface of said middle member, the thickness formed by said middle member and said slab thereon being sufficiently great to bring the upper surface of 65 said slab substantially on a level with the upper surface of the working platform of the press, and means depending from said slab adapted to enter appropriate openings in said middle portion to hold said slab in 70 place on said middle portion.
- In testimony whereof I hereunto affix my signature in the presence of two witnesses.
- PRINCE A. GARDNER.
